UNITED STATES PATENT OFFICE

1,952,382

TISSUE CONTAINER

Charles A. MacGregor, Kooskia, Idaho

Application July 14, 1932, Serial No. 622,514

1 Claim. (Cl. 206—57)

This invention relates to an improved tissue container and is particularly adapted for use in conjunction with paper handkerchiefs and the like.

One object of the invention is to provide a tissue container which is so formed that, after the initial packing, it will be closed so that the contents will be kept in a thoroughly sanitary condition, but which may be readily opened to permit withdrawal of the contents.

Another object of the invention is to provide a tissue container which may be formed of a single blank which will be reinforced so that it will be strong and durable.

A further object of the invention is to provide a tissue container wherein the tissue carried therein will be folded in such a manner that the withdrawal of one handkerchief will present a portion of a succeeding handkerchief to an opening for withdrawal.

And a still further object of the invention is to provide a tissue container which will be characterized by simplicity and efficiency and which may be manufactured cheaply so that quantity production without the sacrifice of quality may be had.

Other and incidental objects of the invention, not specifically mentioned in the foregoing, will be apparent during the course of the following description.

In the drawing forming a part of this application,

Figure 1 is a perspective view of the device as it would appear before being initially opened,

Figure 2 is a perspective view showing the device with the flap opened and showing the pull tab which is connected to the first handkerchief,

Figure 3 is an enlarged vertical sectional view of the device on the line 3—3 of Figure 2, looking in the direction indicated by the arrows,

Figure 4 is an enlarged vertical sectional view on the line 4—4 of Figure 2, looking in the direction indicated by the arrows,

Figure 5 is an enlarged fragmentary vertical sectional view taken on the line 5—5 of Figure 4,

Figure 6 is a plan view showing the container as it would appear as a blank, and

Figure 7 is a diagrammatic view showing the manner of folding the handkerchiefs to be carried in the container.

Referring now more particularly to the accompanying drawing, the numeral 1 indicates, in general, a container which is formed of a single blank, preferably of cardboard. When assembling the container the blank, shown in Figure 6,

is folded to define a top wall 2, a bottom wall 3, bottom flaps 4 and 5, end walls 6 and side walls 7. The end walls 6 are provided at their ends with pairs of tongues 8 and 9, the end wall carrying the tongues 8 being projected to form a flap 60 10. The bottom wall 3 is also projected to form a flap 11. As best shown in Figure 4 of the drawing, the pairs of tongues 8 and 9 are folded inwardly and lie against the inner face of the side walls 7. The flap 11 is folded to extend at right angles to the wall 3 and terminates against the wall 2, while the flap 10 is folded to overlie the lower face of the wall 3 at the end thereof. It will be seen that a double end wall is provided for the container. The bottom flaps 4 and 5 are 65 folded toward each other to overlie the wall 3 and the flap 10, and said flaps 4 and 5 are glued or otherwise secured to the wall 3 and to said flap 10. 70

The completed container is normally provided with a covering of cellophane, indicated by the 75 numeral 11'.

The top wall 2 of the container is provided near one side thereof with a transverse slit 12 the ends of which are curved laterally in spaced relation to the adjacent end walls of said container to define a path of substantially U-shaped outline. The top wall 2 of said container is also provided with a crease or fold line 13 which extends in a straight path between and connects the laterally curved ends of the slit to form a tongue 85 or flap 14, hereinafter to be described in detail. A string 15 is carried beneath the wall 2 of the container and has a portion thereof extending through the cellophane cover 11'. If desired, the cellophane cover may be so folded that the seam thereof will be disposed immediately above one end of the slit so that the portion of string may pass through said cover at said seam. The other end of said string projects beneath the flap 14 and is anchored at the opposite end of the slit so that when it is desired initially to open the container, the string may be engaged and pulled through the slit, the slit providing a guide so that the tongue or flap 14 will be freed. The flap may then be lifted to permit ready access to the interior of the container through a slot 17 defined by said flap. It should be understood that the tongue or flap 14 will be folded back along the crease 13. The string is provided at its end with a tab 16 to facilitate manual engagement.

Normally carried in the container are handkerchiefs 18 which are preferably formed of a light-weight, relatively thin paper, such as the well-known tissue paper. As best seen in Figure 7 of the drawing, the handkerchiefs are folded

to a substantially Z shape and are provided with short top portions 19 and long bottom portions 20. The handkerchiefs are interfolded by extending the lower ends of the portions 20 of one handkerchief beneath the short portion 19 of the next succeeding handkerchief. In this manner, when one handkerchief is withdrawn from the container a portion of the next one will be presented so that they may be conveniently grasped and removal thereof readily effected. To facilitate the starting of a handkerchief more readily, I provide a pull tab 21 which is of substantial Z-shaped fold and is interfolded with the first, or top, handkerchief. The upper portion of the pull tab may have the word "pull" or some other suitable indicia printed thereon.

It will readily be understood that little or no difficulty will be encountered in withdrawing the handkerchiefs from the container.

Attention is directed to the fact that after the desired number of handkerchiefs have been withdrawn, the flap 14 may be swung downwardly on the fold line 13 so as to close the slot 17 and keep the remainder of the handkerchiefs within the container in a sanitary condition. It will thus be seen that the handkerchiefs within the container will be protected from moisture and dirt at all times.

The cellophane cover protects the container so that soiling of the container is prevented.

It will be readily seen from the foregoing that I have provided a simple and highly efficient tissue container.

Having thus described the invention, I claim:—

A handkerchief container comprising a flat substantially rectangular shallow box including integral bottom, top, side and end walls, the top of the box being provided with a transverse slit disposed adjacent to and parallel with one of the side walls of the box, said slit having its opposite ends terminating short of the adjacent end walls of the box and extended laterally in the direction of said side wall, the ends of the lateral extensions of the slit being connected by a straight fold line to form a normally closed flap, a cover entirely enveloping the box, and a single pull string having one end thereof secured to the inner face of the top of the box at one of the laterally extending ends of the slit and having its intermediate portion extending beneath the flap and cooperating with the transverse slit for initially cutting the cover at said slit, the other end of the pull string being extended through the top of the box and said cover at the other laterally extended end of the slit and provided with a terminal finger engaging tab bearing against the cover adjacent one end of the top of the box.

CHARLES A. MACGREGOR.
